UNITED STATES PATENT OFFICE.

ANTHONY H. WEBER, OF NEW ORLEANS, LOUISIANA.

WRENCH.

1,175,098.

Specification of Letters Patent. Patented Mar. 14, 1916.

Application filed June 23, 1915. Serial No. 35,799.

To all whom it may concern:

Be it known that I, ANTHONY H. WEBER, a citizen of the United States, residing at New Orleans, in the parish of Orleans and 5 State of Louisiana, have invented certain new and useful Improvements in Wrenches, of which the following is a specification, reference being had to the accompanying drawings.

10 My present invention relates broadly to new and useful improvements in wrenches and has particular reference to those of the type in which the movable jaw is provided with a threaded shank whereon operates a 15 nut, for adjusting the movable jaw with respect to the fixed jaw.

One of the principal objects of the present invention is to form the adjusting nut employed in connection with the threaded 20 shank of the movable jaw, as a two piece element which may be locked together for rotation as a unit when the movable jaw is to be adjusted or may be disposed in such 25 relation to each other that the threaded shank of the movable jaw may be moved, unrestrictedly through the nut and the jaw thus quickly moved to the approximate adjusted position desired.

The above, and other incidental objects of 30 a similar nature, which will be hereinafter more specifically treated are accomplished by such means as are illustrated in the accompanying drawings, described in the following specification, and then more particularly pointed out in the claim which is 35 appended hereto and forms part of this application.

With reference to the drawings, wherein there has been illustrated the preferred embodiment of this invention, as it is reduced to practice, and throughout the several views of which similar reference numerals designate corresponding parts, Figure 1 is a side elevation; Fig. 2 is a detail view in plan of 40 the bottom face of the upper section of the adjusting nut; Fig. 3 is a detail view in plan of the upper face of the lower section of the nut; Fig. 4 is a section on the line 4—4, of Fig. 1; and Fig. 5 is a detail vertical section 45 taken through the nut and showing the two sections thereof arranged for adjustment of the movable jaw.

In construction, my wrench as embodied 50 in the accompanying drawings, takes for the most part, the form of an ordinary wrench, differing therefrom mainly in the construc-

tion of the adjusting means. Preferably the shank 10 of the wrench is equipped with an integral fixed jaw 11, and a handle 12. A movable jaw 13 is mounted for sliding movement on the shank of the wrench, whereby it may be adjusted toward or away from the fixed jaw in the usual manner. The handle 12 is relatively wide and is provided at its junction with the shank, with a lateral 60 shoulder 14, which lies on that part of the shank from which the movable jaw projects. A longitudinal bore, indicated at 15 in Fig. 1, is formed in the handle and is so located that its outer end opens through the shoulder 65 at the approximate center thereof. In this bore is received the threaded shank or adjusting stem 16, which member extends at right angles to the movable jaw, from the outer face thereof. As disclosed best in Fig. 70 1, the member 16 is spaced from the shank of the wrench and is disposed in parallel 75 relation thereto.

The adjusting stem or shank 16 is non-circular in cross section, being provided 80 with two flat parallel faces 17 and 18 and with two opposed transversely curved faces 19 and 20. These two curved faces are provided with threads, as in Fig. 1, so that when the nut, generally designated in Fig. 85 1, by the letter A, is properly set and rotated, the adjusting stem will be moved longitudinally with respect to the wrench shank, for adjusting the movable jaw with 90 respect to the fixed jaw.

The adjusting nut heretofore generally 95 designated by the letter A, is formed in two separate sections 21 and 22, which members are respectively shown in detail in Figs. 2 and 3. The section 22 is provided with a flat upper face, wherein is formed an arcuate groove 23. The opening 24 through the member 21 is provided with two smooth curved walls 25 and 26 and two curved walls 27 and 28, which are opposed to each other and each of which is provided with worm threads, as shown best in Fig. 5. The section 21 is provided with an opening having the characteristics of the opening 24 and has a flat lower face, indicated at 29. A stud 30 depends from the face 29. This stud is designed to seat in the groove 23 for a purpose which will be hereinafter explained. The lower face of the nut section 21 is provided with a stop shoulder 31, from the base of which the lower face extends upward, to the apex of the shoulder. This 100 105 110

shoulder is adapted to engage with a stop shoulder 32, which is adapted to limit the rotation of the section 22 in one direction upon the shoulder 15, for a purpose which 5 will be hereinafter explained.

Attention is now directed to Fig. 4, wherein it will be seen that the two sections of the nut may be so arranged with such respect to each other that the smooth walls 10 of the openings through the nut are vertically alined and the threaded walls of the openings also aline. On the other hand, the two sections of the nut may be arranged, as in Fig. 4, to dispose the threaded walls 15 of the opening of the one section in alinement with the smooth walls of the opening in the other section.

The actual construction and arrangement of the several parts of the invention, being 20 thus disclosed, it now remains to describe the manner in which the nut is manipulated when the movable jaw is to be adjusted. When it is desired to displace the movable jaw from engagement with a pipe or other 25 article held by the wrench, and to quickly produce a wide space between the fixed and movable jaws, the section 21 is turned upon the section 22 in a right-hand direction, until the stud 29 is engaged in the end of 30 the groove 23. When the stud is thus disposed, the smooth walls of the opening through the two sections of the nut will be alined. Then, by continuing to turn the 35 upper section 21, it is obvious that the two sections will rotate in the same direction as a unit, until the shoulder 32 engages with the shoulder 31. When these two shoulders are engaged, the smooth walls of the nut A are disposed opposite to the threads on the 40 two curved faces 19 and 20 of the adjusting stem or shank 16, while the threaded walls of the nut are disposed opposite to the flat parallel faces 17 and 18 of the stem 16. Thus the adjusting stem 16 may be slid back into 45 the bore 15, without any opposition, so as to quickly space the movable jaw from the fixed jaw.

When the movable jaw is to be minutely adjusted, the section 21 of the nut is turned 50 to the left, until the stud 29 engages the other end of the groove 23, in which position of the stud the threads of the one section are alined with the smooth unthreaded faces of the opening in the other section. When 55 the two sections of the nut are thus disposed, the nut is adapted to be rotated as a unit, and to have its threads engaged at all times with the threads of the member 15.

In this connection, it will be apparent that when the threads of the section 21 are moved 60 during the rotation of the nut, to a position opposite the flat faces of the member 18, the threads of the other nut section 22 will be in engagement with the threads of the member 15.

Obviously, the nut may be initially adjusted to a considerable range by so disposing the two sections of the nut that the member 15 may freely slide therethrough. Then the more minute adjustment of the 70 jaw may be accomplished by turning the nut so that the threads of the two sections thereof will continuously engage with the threads of the member 15. The jaw may be held against movement from the desired adjusted position by allowing the two sections of the nut to remain in such position that the stud 29 engages in the right-hand end of the groove 23.

Having thus described this invention, 80 what is claimed is:—

A wrench including a shank having a fixed jaw on one end and a laterally offset handle portion on its other end, said handle being provided with a rectangular longitudinal bore, an adjustable jaw slidable on the wrench shank, a stem fixed at one end to said jaw and slidably engaged in the bore of the handle, said stem being provided with threads on its opposite faces, and an adjusting nut consisting of two superposed sections each being provided with internal oppositely disposed quarter threads, said nut sections being further provided with co-engaging means for limiting their relative 95 turning movement in either direction, whereby the quarter threads on the nut sections may each be engaged with the threads of said slidable stem or the threads on opposite sides of the nut sections alined with each other to permit of the sliding movement of said stem through the nut sections, the end of said handle and one of the nut sections being provided with shoulders adapted for contact with each other in the latter arrangement of the nut sections to prevent a further unitary rotation in one direction of the nut with respect to said stem.

In testimony whereof I hereunto affix my 110 signature in the presence of two witnesses.

ANTHONY H. WEBER.
